United States Patent Office

Des. 198,412
Patented June 9, 1964

198,412

TRIPOD HEAD

Paul C. Mooney, Northbrook, Ill., assignor to Quick-Set,
Incorporated, Skokie, Ill., a corporation of Illinois

Filed Sept. 6, 1963, Ser. No. 76,499

Term of patent 14 years

(Cl. D61—1)

FIG. 4

FIG. 5

FIG. 1 is a side elevational view of a tripod head showing my new design;

FIG. 2 is a top plan view thereof;

FIG. 3 is a rear elevational view thereof;

FIG. 4 is an elevational view of the side opposite that shown in FIG. 1; and

FIG. 5 is a front elevational view thereof.

Portions of the elevating post are broken away in FIGS. 3, 4 and 5 for convenience of illustration.

I claim:

The ornamental design for a tripod head, as shown and described.
